UNITED STATES PATENT OFFICE.

HENRY C. DORN AND HERMAN A. LUEDKE, OF MILWAUKEE, WISCONSIN, ASSIGNEES
TO D & L MFG. CO., OF MILWAUKEE, WISCONSIN, A CORPORATION OF WISCONSIN.

REINFORCING-CORNER FOR RECEPTACLES.

1,397,623.

Specification of Letters Patent. Patented Nov. 22, 1921.

Application filed February 16, 1920. Serial No. 359,025.

To all whom it may concern:

Be it known that we, HENRY C. DORN and HERMAN A. LUEDKE, citizens of the United States, and residents of Milwaukee, in the 5 county of Milwaukee and State of Wisconsin, have invented new and useful Improvements in Reinforcing-Corners for Receptacles, of which the following is a description, reference being had to the accompanying drawings, which are a part of this specification.

The present invention relates to certain new and useful improvements in reinforcing corners for receptacles and has for one of 15 its objects to provide a receptacle or container having means for holding the receptacles firmly stacked one above another and to permit the convenient stacking or removing of the receptacles and to reinforce the 20 bottom portion of the receptacle.

Another object of the invention is to provide a receptacle in which the corner portions of the receptacles are reinforced by the means serving to maintain the receptacles in stacked relation.

With the above and other objects in view which will appear as the description proceeds our invention resides in the novel construction, combination and arrangement of 30 parts substantially as hereinafter described and more particularly defined by the appended claims, it being understood that such changes in the precise embodiment of the herein disclosed invention may be made as 35 come within the scope of the claims.

In the accompanying drawing we have illustrated one complete example of the physical embodiment of our invention constructed according to the best mode we have 40 so far devised for the practical application of the principles thereof, and in which:

Figure 1 is a top plan view of one end portion of a container or receptacle provided with our reinforcing corner.

Fig. 2 is a sectional view through one side wall of the container and illustrating the device as in stacked relation with another container depicted in conventional lines.

Fig. 3 is a perspective view of one of the 50 upper reinforcing corners, and

Fig. 4 is a perspective view of one of the lower reinforcing corners.

Referring now more particularly to the accompanying drawing, the numeral 5 design-

nates a wooden rectangular box-like structure having thin side wall portions 6 and heavier end portions 7 which are nailed or otherwise fastened together in any manner desired. The lower corners of the receptacle are reinforced by lower angular channeled corner members 8, which are fastened to both the ends and sides of the box by rivets 9.

The upper corner edge portions of the box are also reinforced by upper angular 65 reinforcing members 10, which are also connected to the box by rivets or other fastening means 11. The upper reinforcing members 10 have inwardly offset and upwardly extending angular stacking projections 12, 70 which are shaped to fit or telescope with the lower reinforcing corner members 8 and hold the boxes in stacked relations.

The reinforcing members 8 and 10 are each formed from a single sheet of metal and 75 serve to substantially reinforce the corners of the box or receptacle 5. The lower member 8 is channeled as at 13 to receive the adjacent side and end portions of the container or box 5 as before described, and thus forms 80 a firm brace for the lower corners. The upper members 10 are also struck from a single sheet of material and substantially reinforce the adjacent corner portions of the box.

What we claim as our invention is:

1. A device of the class described comprising a reinforcing corner, a raised portion formed thereon and extending inwardly from the edges thereof, and a second reinforcing corner shaped to extend outside of the raised portion of the other corner.

2. A combined corner reinforcement and stacking device for receptacles comprising a reinforcing corner member, and an inwardly offset and upwardly extending stacking projection formed on said reinforcing corner member and engageable with the inner edge portions of the adjacent corner of a receptacle placed over the receptacle 100 carrying said corner member.

3. A combined corner reinforcement and stacking device for receptacles comprising an upper reinforcing member secured to a receptacle at each upper corner, inwardly offset and upwardly extending stacking projections formed on said reinforcing members, and a lower reinforcing member secured to

the receptacle at each lower corner and adapted to engage outside of and over the stacking projections of a receptacle disposed therebeneath.

5. 4. A combined corner reinforcement and stacking device for receptacles comprising an upper reinforcing member secured to a receptacle at each upper corner, inwardly offset and upwardly extending stacking projections formed on said reinforcing members, and a lower channeled reinforcing member secured to the receptacle at each lower corner and adapted to engage outside of and over the stacking projections of a receptacle disposed therebeneath.
10. 5. A combined corner reinforcement and

stacking device for receptacles comprising an angular reinforcing member secured to the upper edge of a receptacle at each corner, inwardly offset and upwardly extending angular stacking projections formed on said reinforcing members, and an angular channeled member secured to the lower edge of the receptacle at each corner, said stacking projections extending within the inner edge 20 portions of said angular channeled members when a plurality of receptacles are superimposed one over the other.

In testimony whereof, we affix our signatures.

HENRY C. DORN.
HERMAN A. LUEDKE.
